UNITED STATES PATENT OFFICE.

WALLACE B. MARTIN, OF ST. PAUL, MINNESOTA.

VALVE GRINDING AND RESEATING TOOL.

1,357,408.

Specification of Letters Patent.

Patented Nov. 2, 1920.

Application filed June 3, 1919. Serial No. 301,532.

To all whom it may concern:

Be it known that I, WALLACE B. MARTIN, a citizen of the United States, residing at St. Paul, in the county of Ramsey and State 5 of Minnesota, have invented certain new and useful Improvements in Valve Grinding and Reseating Tools; and I do hereby declare the following to be a full, clear, and exact description of the invention, such as 10 will enable others skilled in the art to which it appertains to make and use the same.

My present invention relates to valve-grinding and reseating tools, and is in the nature of an improvement on my United 15 States Letters Patent, #1,286,378, issued of date December 3, 1918.

To the above end, the invention consists of the novel devices and combinations of devices hereinafter described and defined in 20 the claims.

In the accompanying drawings, which illustrate the invention, like characters indicate like parts throughout the several views.

25 Referring to the drawings:—

Figure 1 is a fragmentary plan view of an internal combustion engine, the head of which is removed to expose the valves, and secured to the cylinder casting is the improved tool positioned to oscillate one of the valves;

Fig. 2 is a view principally in vertical section taken on the irregular line 2—2 of Fig. 1, on an enlarged scale; and

35 Fig. 3 is a detail view on an enlarged scale, with some parts sectioned on the line 3—3 of Fig. 1.

The numeral 4 indicates the cylinder casting of an internal combustion engine, the head of which is removed to expose the valves 5 and valve seat 6. Bolts 7, one of which is shown in Fig. 2, are applicable for screw-threaded engagement with bores 8 in the engine casting 4 to detachably secure 40 the cylinder head thereto. In grinding one of the valves 5, a coiled spring 9 is placed around the stem thereof between the valve head and the bottom of the valve chamber, and which spring is of such length as to lift 45 the respective valve above its seat, as shown in Fig. 2. In the top of each valve 5 is a pair of diametrically opposite wrench pin holes 10.

The parts thus far described are of well 55 known construction and have been illus-

trated simply for the purpose of showing the invention applied in working position.

Referring now to the improved tool, the numeral 11 indicates a cast-bearing head mounted for horizontal swinging movement 60 on the bolt 7 with freedom for limited vertical sliding movement and which bolt, as shown in Fig. 2, is secured in one of the bores 8, and affords the support for the tool. A vertical seat 12 is formed in the 65 head 11 and arranged to be brought into axial alinement with either of the two valve seats 6 between which the bolt 7 is located.

To rigidly hold the bearing head 11 against lateral swinging movement with its 70 seat 12 in axial alinement with either one of the respective valve seats 6, there is provided an anchor pin 13. This anchor pin 13 is arranged to project through either one of two bores 14, formed in ears 15 on the 75 longitudinal edge portions of the bearing head 11 and which bores are located equidistance on each side of a line that intersects the axis of the bolt 7 and seat 12. It will be noted that the anchor pin 13 is 80 upwardly tapered and affords a support for the bearing head 11 to hold the same above a lock nut 16 on the bolt 7. The anchor pin 13 has a base 17, which rests directly on the top of the cylinder casting 4, 85 and is provided with a bore through which the bolt 7 loosely projects, and which base is held in different adjustments by the lock nut 16.

A tubular spindle 18 is mounted in the 90 seat 12 for both rotary and endwise movements, and has on its upper end a hand crank 19 secured thereto by a transverse pin 20. Extending axially through the tubular spindle 18 is a stem 21, having on its lower 95 end below said spindle a valve grapple 22 in the form of a fork, the prongs of which are arranged to enter the pin holes 10 in any one of the valves 5. The upper end of the stem 21 is expanded to afford a bearing head 23, through which the pin 20 extends and supports the valve grapple 22 for common rotation with the tubular spindle 18, but with freedom for lateral wobble motion in respect thereto. The purpose of the 100 bearing head 23, which engages the internal wall of the tubular spindle 18, is to hold the upper end of the stem 21 against lateral movement, but permit the required universal lateral wobble movement on the valve 110

grapple 22. It will be noted that the upper end of the stem 21 projects above the tubular spindle 18 to afford a hand piece by which the valve grapple 22 may be guided into the pin holes 10 of one of the valves 5.

The parts of the improved tool thus far described are fully described and broadly claimed in my heretofore mentioned patent.

To properly grind the valve, it is, of course, necessary to apply sufficient pressure to the hand crank 19 to overcome the spring 9 and carry the engaged valve 5 into the seat on which, together with the valve, is placed a valve grinding compound. It is also highly essential in grinding a valve to constantly release the pressure on the tool sufficiently to allow the spring 9 to lift the valve in order that the same may be given a slight rotation while out of engagement with its seat and then again pressed onto its seat. This constant applying of pressure to the tool and then releasing the same is very tiresome and also makes the work of grinding a valve rather slow.

The purpose of my present invention is to provide means for automatically lifting the valve grapple during either the complete rotations or oscillations thereof, without releasing the pressure on the hand crank 19, and thereby allow the spring 9 to lift the valve from its seat so that the same may be carried a short circumferential distance out of engagement with the seat, and then again brought into contact with said seat.

As one means for accomplishing this result, there is shown in the accompanying drawings two circumferentially spaced lugs 24 integrally formed with the hub of the hand crank 19 and each of which is provided on its lower face with oppositely extended cam surfaces 25 arranged to engage a vertical abutment 26 on the bearing head 11 in either direction of rotation of the hand crank 19. As shown, this abutment 26 is in the form of a screw having a round head with which the cams alternately engage when the hand crank 19 is given only partial rotation. This abutment 26 has screw-threaded engagement with the bearing head 11 and is positively held in different set positions by a lock nut 27. Obviously, by vertically adjusting the abutment 26, the lift-

ing movement imparted to the valve grapple 22 by the engagement of the lugs 24, with said abutment, may be varied at will. 55

While in the present drawings there is shown two cam lugs and one abutment, and it is of course understood that one or more cam lugs may be employed and likewise one or more abutments may be provided. It is also understood that the abutment may be carried by the crank and the cam lugs formed with the bearing head. It may be further noted that a roller abutment may be provided in place of the one shown. 60 65

What I claim is:—

1. A valve-grinding tool comprising a bearing head, a valve grapple rotatively mounted in said head with freedom for lifting movement, means for rotating the valve grapple, a cam lug, an abutment co-operating with the cam lug to lift the valve grapple and then release the same, and means for adjusting the abutment to vary the lift of the valve grapple. 75

2. A valve-grinding tool comprising a support, a bearing head adjustably mounted on the support, a stem mounted in the bearing head with freedom for endwise and rotary movement, a valve grapple carried by the stem, a crank for rotating the stem and imparting downward pressure thereon, an abutment on the bearing head, and a cam surface on the crank arranged to intermittently engage the abutment to lift the stem 80 and then release the same. 85

3. A valve-grinding tool comprising a support, a bearing head adjustably mounted on the support, a stem mounted in the bearing head with freedom for endwise and rotary movement, a valve grapple carried by the stem, a crank for rotating the stem, and imparting downward pressure thereon, a vertically adjustable abutment on the bearing head, and a cam surface on the crank 90 arranged to intermittently engage the abutment to lift the stem and then release the same. 95

In testimony whereof I affix my signature in presence of two witnesses.

WALLACE B. MARTIN.
